TOOL FOR MAKING DYNAMO ELECTRIC
MACHINE ELEMENTS

Vincent G. Apple, deceased, late of Dayton, Ohio,
by Herbert F. Apple, Edward M. Apple, and
Gourley Darroch, executors, Dayton, Ohio.

Original application June 10, 1929, Serial No.
369,564. Patent No. 1,934,903, dated November
14, 1933. Divided and this application Novem-
ber 1, 1933, Serial No. 696,288

1 Claim. (Cl. 29—84)

This invention is a division of a co-pending application S. N. 369,564 and patented Nov. 14, 1933, No. 1,934,903 and relates to tools for making dynamo electric machine elements of the 5 type comprising a hollow cylindrical core with a winding disposed in a series of slots spaced about its inner circumference.

The object of the invention is to provide a tool to facilitate placing and affixing the winding in 10 the slots.

The process by which this object is attained, together with the tool and the manner of using it, is hereinafter specifically described, reference being had to the drawing, wherein

15 Fig. 1 shows a perspective view of the core.

Fig. 2 shows one of the coils as first formed.

Fig. 3 shows one of the coils as reshaped and further insulated.

Fig. 4 shows one of the coils in process of being 20 entered into the slots of the core.

Fig. 5 shows the assembled core and coils.

Fig. 6 is a perspective view of the tool for seat- 15 ing and affixing the coils in the slots.

Fig. 7 is an axial section through the core and 25 coils assembly with the tool in use.

Similar numerals refer to similar parts throughout the several views.

The core 10 is composed of a plurality of 30 laminæ 11. A central opening 12 has winding slots 13 spaced apart by teeth 14 around its circum- 35 ference. To adapt the core to a bipolar winding two teeth are shortened as at 16.

Two coils 17 are required, one of which is shown 35 in Fig. 2. These coils are preferably wound of a single piece of fibrous covered wire starting at 18 and ending at 19, and are wound in three interconnected sections 21, 22 and 23, joined together at 24 and 26. Before they are wound the fibrous covering on the wire is preferably saturated and dried to such a degree that it may be conveniently handled but not to an extent to make the 40 coating brittle.

Before the coils 17 are placed on the core they are preferably reshaped and further insulated. Fig. 3 shows a cross section through a reshaped core 17 which is ready for assembly with the core 10, the several sections having been formed so that the end turns 28 are of semi-circular contour, but the coil sides 32 are straight. The coil sides 32 are pressed to flatten them, preferably after the core slot linings comprising U shaped pieces of insulation treated fabric 34 are lapped around them, pressure being applied to the sides 45

of the U's to make the cross section of the coil sides narrower but higher.

Fig. 4 shows the core 10 after one of the reshaped coils 17 has had the coil sides 32, Fig. 3, entered in the core slots 13. After the coil sides are pressed downwardly into the slots as far as possible by hand, the free ends of the U shaped slot liners are lapped over each other as at 36, although the lapped over ends may bulge from the slots and extend slightly above the ends of 10 the core teeth 14.

Fig. 5 shows the core 10 with the entire winding assembled therein, and all of the free ends of the U shaped insulation treated fabric slot liners 34 lapped over each other as at 36, in 15 which condition it is ready to have the tool 37, Fig. 6, applied.

The tool 37, Figs. 6 and 7 comprises a base 38 having as many equally spaced radial slots 39 in its upper surface as there are teeth in the 20 core 10. A cover plate 41 is secured to the base 38 by screws 42. This cover plate converts the slots 39 into substantially square, radially extending tunnels. L shaped jaws have the lower horizontal portion 43 of the L's slidably fitted to these 25 tunnels 39 so that the jaws have radial movement relative to the base 38. The vertical legs 44 of the L shaped jaws have one edge 46 somewhat slanting so that the space within the set of jaws, when all are in place, tapers from the top 30 downwardly. A tapered plug 47 has shallow equally spaced longitudinal slots 48 and the slanting edges 46 of the jaws extend slightly into these slots. It will be seen that vertical movement of the plug 47 will produce simultaneous radial 35 movement of the jaws.

When a core and coil assembly has been prepared as in Fig. 5, it is placed over the tool 37 as shown in Fig. 7 with the vertical leg 44 of a jaw over the entrance of each slot 13 against the 40 lapped over ends 36 of the slot liners 34. The plug 47 is then pushed downward until the jaws 44 extend slightly into the entrances of the core slots as at 49. Without removing the tool 37 the core and coils assembly shown in Fig. 7 is now 45 heated so that the coatings of cementitious insulation on the wire will first unite into a single mass, and then, by continued applications of heat, the mass with the wire imbedded in it will be hardened. When the insulation mass is sufficiently hard the tool 37 is removed.

When the core and coils assembly is separated from the tool 37 the coils are rigid, and the end turns 28 may not again be displaced, and the coil sides 32 will not again expand and extend 55

above the ends of the core teeth 14. The completed element may be mounted in a separate housing of metal or of other material, or it may have a housing of thermoplastic insulation molded to and about it.

5 In a copending application Serial Number 369,564, filed June 10th, 1929, of which this application is a division, is claimed the method of making a dynamo electric machine element herein disclosed and there is shown therein but not claimed the tool 37 which is the subject of the present application. The claim in the present application, therefore, confined to the tool 37 herein shown.

10 15 What is claimed is:

A coil seating tool of the character described comprising a base, a plurality of horizontally

disposed radial grooves in said base, a plurality of radially movable jaws slidably secured in said grooves, said jaws having vertically extending parts at their inner ends arranged in the form of a cylindrical cage, said vertically extending parts being wider at the base than at the upper end the outer edges of said parts all being parallel to the axis and the inner edges at an angle thereto, and a downwardly movable center plug having grooves on its outer face fitted to the inner tapered edges of the said vertically extending jaw portions.
